UNITED STATES PATENT OFFICE.

CHARLES LIONEL MARCUS AND JOSEPH A. FIELDS, OF NEW YORK, N. Y.

DESIGN FOR A PERFUME BOTTLE.

Application filed December 12, 1924, Serial No. 11,682, and in France February 12, 1924. Term of patent
 $3\frac{1}{2}$ years.

To all whom it may concern:

Be it known that CHARLES LIONEL MARCUS and JOSEPH A. FIELDS, citizens of the United States, and residents of the city of New York, in the county of New York and State of New York, have invented a new, original, and ornamental Design for Perfume Bottle, of which the following is a specification, reference being had to the accompanying drawing, forming part thereof, in which—

Fig. 1 is a plan view of a perfume bottle embodying our new design;

Fig. 2 is a front elevational view thereof; Fig. 3 is a rear elevational view thereof.

We claim:

The ornamental design for a perfume bottle as shown.

Dated New York city, November 24th 1924.

CHARLES LIONEL MARCUS.
JOSEPH A. FIELDS.
